SHEET METAL WORM

Walter J. Stuber, Philadelphia, Pa., assignor to
 Carey-McFall Co., Philadelphia, Pa., a corporation of Pennsylvania

Application June 13, 1936, Serial No. 85,170

7 Claims. (Cl. 74—458)

This invention relates to the slat-tilting mechanism of a Venetian blind. The present application includes divisible subject matter originally disclosed in my copending application Serial No. 5 52,725, filed December 3, 1935 and additional matter constituting a continuation thereof.

The invention involves primarily a novel form of worm gear employed in the tilting mechanism and wherein the worm is composed of a plurality 10 of sections each constituting a predetermined segment of a convolution of the worm spiral and which may vary from a full three hundred and sixty degree segment to any divisible part thereof, depending upon the nature of the worm desired. 15 The object of the invention is to provide a quiet acting worm gearing which will tilt the slats and lock them in any desired position with a minimum of effort and at a maximum speed.

The construction and operation of the invention forming the subject matter of the present application will be fully disclosed hereinafter, reference being had to the accompanying drawing, of which:

Fig. 1 is a front elevation of the tilting mechanism;

Fig. 2 is a face view of the tilting mechanism, partly in section as viewed on the line 2—2, Fig. 1 and showing one form of worm within the scope of the invention;

Fig. 3 is a sectional elevation taken on the line 3—3, Fig. 2;

Figs. 4, 5, and 6 illustrate details of the worm shown in Figs. 2 and 3;

Figs. 7 and 8 show details and assembly of a development of the worm shown in Figs. 1 to 6;

Fig. 9 is a view similar to Fig. 2 showing a still further development of the worm;

Fig. 10 shows a face view in detail of one of the worm segments of Fig. 9;

Fig. 11 is a top edge view of the segment shown in Fig. 10;

Fig. 12 is a side edge view of the segment shown in Figs. 10 and 11; and

Fig. 13 is a section taken on the line 13—13, Fig. 10.

The device as originally disclosed in application Serial No. 52,725 includes the features disclosed in Figs. 1 to 6 inclusive.

The blind structure usually comprises a head 50 rail (not shown) which is adapted to support and solely carry the whole of the blind structure, including the tilting mechanism of the present case.

Secured to the under side, and at the opposite 55 ends respectively, of the head rail is a pair of

blind-supporting brackets, one of which is shown at 2, which support the tilting rail 4. The blind proper is attached to the tilting rail 4 and, as usual, comprises a series of substantially parallel, horizontally disposed and vertically spaced slats which are supported by and between laterally spaced pairs of ladder tapes. The ladder tapes consist of the usual side tapes connected by the usual cross tapes which underlie the slats and retain said slats in said predetermined vertically spaced relation to each other, when the blind is in the fully extended or maximum low position. The upper ends of the ladder tapes are connected to the tilting rail 4.

In order to provide for pivotal or lateral tilting 15 movement of the tilting rail 4 and the slats carried thereby the tilting rail 4 is provided at one end with a suitable trunnion which has bearing in the bracket located at that end of the tilting rail which has been omitted from the present drawing.

The opposite end of the tilting rail 4 is mounted on, carried by, and permanently secured to an element forming a detachable part of the tilting mechanism. In the present instance, such element comprises a plate or wheel 5 in which is secured a laterally extending trunnion stud 6, said stud being pivotally and removably mounted in a bearing opening formed in the bracket 2 and arranged in axial alignment with the trunnion at the opposite end of the tilting rail 4.

The plate 5 has a lateral extension 7, below the pivot 6, which extends under and is secured to the under surface of the tilting rail 4, by screws, bolts, or other suitable means.

For the purpose of tilting the rail 4 and the slats carried thereby to desired angles relative to the plane of the window, the plate 5 is provided with gear or worm teeth 9 throughout a segment of a circle swung from the axis of the stud 6, as clearly shown in Fig. 2.

Mesling with the teeth 9 of the gear segment is a double pitch worm 10. Said worm is composed of two identical parts 10a—10a pressed from flat sheet metal and each comprising a hub section 11 and a segmental rim section 12 formed integral therewith, said rim section, in that form of the worm shown in Figs. 2 to 6 inclusive comprising a segment of a circle to the extent of substantially 190°.

The double pitch worm is formed by assembling two identical parts, see Figs. 5 and 6, in reverse order with respect to each other with the hub sections 11 thereof in axial alignment one with the other, and the two segmental rim sections 12, 12 55

in overlapping relation at the ends 13 and 14 thereof and forming a full circle with the overlapping ends spaced apart laterally, i. e. axially of the worm, to provide an opening 15 of sufficient width to accommodate one of the teeth 9 of the tilting plate or wheel 5 therebetween, the peripheral edges and margins of the segments 12, 12 of the worm parts 10a—10a working respectively in alternate spaces between the teeth 9 of the tilting plate 5, whereby the effect of the double pitch worm and worm gear is provided.

Fig. 6 illustrates the two parts 10a—10a in the course of being assembled to provide the complete worm 10 shown in Figs. 2 and 3.

15 By rotation of the worm 10, the tilting plate 5 may be rocked about the common axis of the trunnions of the tilting rail 4 to an extent of substantially 180°, whereby the slats may be rocked in either direction from their normally parallel 20 horizontal planes, for example, to a substantially vertical plane and wherein the edges of the slats will lie in closely adjacent or overlapping relation to each other, to close the window opening substantially completely.

25 The tilting movement is limited by the ends of the worm sections engaging untoothed portions of the tilting plate or wheel 5 when said plate has arrived at either one or the other of its limits of tilting.

30 The tilting worm is secured to one end of a tilting spindle 20 which is flattened on one or both sides adjacent one end to receive a correspondingly shaped opening 21 in each of the worm sections 10a and by which the two sections 35 10a—10a of the worm are keyed to the spindle 20, said sections being firmly held in fixed relation to each other and to said spindle by riveting the end of the spindle over the outer section, as indicated at 21, and pressing the inner section 40 against a shoulder 22 formed on the spindle, as by the above noted flattening of the spindle.

45 The tilting spindle 20 is rotatably mounted in a suitable bearing 23 formed in the bracket 2 by splitting the bracket and pressing alternate portions between the slits outwardly in one direction from the plane of the bracket 2 and the intermediate and outermost portions of the plate in the opposite direction.

50 The end of the spindle 20, opposite to that on which the worm 10 is secured, is provided with a sheave wheel 25 which, like the worm 10, is composed of two disks pressed from sheet metal and of identical construction, these disks being dished and placed together in axial alignment and with 55 their convexed surfaces in abutting relation to each other to provide a groove for the reception of an operating cord or chain 24.

55 In the present instance, a common form of ball chain is provided to pass around the sheave, and 60 in order to prevent a slippage between the sheave and the operating chain the dished disks of which the sheave is composed are radially corrugated adjacent the periphery thereof to provide suitable pockets for receiving the balls of the 65 operating chain.

65 In order to hold the balls within the recesses of the operating sheave a guard 26 is provided around the periphery of the wheel 25, said guard comprising a flange 27 formed on a plate 28 which 70 is freely rotatably mounted on the operating spindle 20 between one end of the bearing 62 and the inner face of the sheave 25.

75 The sheave 25, like the worm 10, is secured to the spindle 20 by riveting a flattened shouldered end of the spindle over the outer disk of the

sheave 25, as indicated at 29 which clamps and keys the two disks of which the sheave is composed rigidly to the spindle and against the second shoulder formed on said spindle.

From the above, it will be seen that by a short 5 movement in either direction of the operating chain 24 the tilting plate 5 through the double pitch worm 10 meshing with the teeth 9 of the tilting plate 5 may be moved to either of its extreme positions and locked therein by the intermeshing of the worm 10 with the worm teeth 9, or at any intermediate position between said extremes.

Fig. 8 shows four discs 10b—10b of the kind shown in Fig. 7, as including each a 180° segment 15 of a convolution of the worm spiral and arranged with the end 13b of one in abutting relation to the end 14b of another of the segments with the side marginal edges 12b—12b flush, to produce a continuous smooth thread of the worm spiral. 20 These parts 10b—10b and 10b—10b are arranged in pairs with the hubs 11b—11b of each pair in axial abutting relation to each other and with a spacer sleeve or collar 30 between the pairs.

Figs. 10, 11, 12, and 13 illustrate a worm where- 25 in each part 10c thereof includes a complete 360° segment of a circle constituting one complete convolution of the worm spiral, each section or part 10c being composed of a circular disc, see Fig. 10, having a central opening 21c in the central hub 30 portion 11c thereof and from which to the outer marginal edge 12c the disc is split radially on the line a—a, providing two ends 13c and 14c. These ends are spread apart axially of the worm, as seen in Figs. 11 and 12 and in that way form the spiral 35 convolution of the worm.

The two sections 10c—10c are fitted together as illustrated in Fig. 13 and in order to do so the hub section 11c of each part 10c is off-set at opposite sides of the split line a—a, as illustrated 40 at 31 in Fig. 13, to opposite sides respectively of a median plane x—x, the offsets 31, 31 being connected by an angular web portion 32 which forms shoulders 33 and 34 on each hub section 11c against which edges 35 and 36 paralleling the 45 split line a—a of the other section abut, the two portions 10c—10c thereby becoming interlocked one with the other to complete the worm which in its assembled form is a double pitch, double spiral worm by which quiet operation is obtained 50 because of the fact that there is at all times more than one tooth of the worm wheel 5 in intermeshing engagement with the worm and this eliminates any noise that may be produced by the half segments of the worm shown in Figs. 55 2 and 3 coming into engagement with the teeth of the worm wheel alternately.

Obviously, the worm shown in Figs. 7 and 8 or that shown in Figs. 9 to 13 may be substituted for the worm shown in Figs. 2 to 6 without departing from the spirit of the invention.

I claim:

1. In a Venetian blind tilting mechanism including a tilting wheel having circumferentially spaced teeth, a worm cooperating with said toothed wheel and comprising a plurality of identical parts respectively including a central hub section and a peripheral marginal section constituting a segment of a convolution of the worm spiral with said hub and marginal sections being integral and of substantially uniform thickness over the entire areas thereof in the direction of the axis of the worm and with the marginal section of each part disposed in a plane arranged at an angle to the plane of the 75

- hub section of said part, said parts being assembled in intermeshing relation to each other with the hub sections thereof in substantially parallel and axial aligned relation one with the other and predetermined portions of said spiral segments of an intermeshing pair of said identical parts spaced apart axially of said worm to receive single teeth of said tilting wheel therebetween.
2. In a Venetian blind tilting mechanism including a tilting wheel having circumferentially spaced teeth, a worm cooperating with said toothed wheel and comprising a plurality of identical parts respectively including a central hub section and a peripheral marginal section constituting at least a 180° segment of a convolution of the worm spiral with said hub and marginal sections being integral and of substantially uniform thickness over the entire areas thereof in the direction of the axis of the worm and with the marginal section of each part disposed in a plane arranged at an angle to the plane of the hub section of said part, said parts being assembled in intermeshing relation to each other with the hub sections thereof in substantially parallel and axial aligned relation one with the other and predetermined portions of said spiral segments of an intermeshing pair of said identical parts spaced apart axially of said worm to receive single teeth of said tilting wheel therebetween.
3. In a Venetian blind tilting mechanism including a tilting wheel having circumferentially spaced teeth, a worm cooperating with said toothed wheel and comprising a plurality of identical parts respectively including a central hub section and a peripheral marginal section constituting a segment greater than 180° of a convolution of the worm spiral with said hub and marginal sections being integral and of substantially uniform thickness over the entire areas thereof in the direction of the axis of the worm and with the marginal section of each part disposed in a plane arranged at an angle to the plane of the hub section of said part, said parts being assembled in intermeshing relation to each other with the hub sections thereof in substantially parallel and axial aligned relation one with the other and predetermined portions of said spiral segments of an intermeshing pair of said identical parts spaced apart axially of said worm to receive single teeth of said tilting wheel therebetween.
4. In a Venetian blind tilting mechanism including a tilting wheel having circumferentially spaced teeth, a worm cooperating with said toothed wheel and comprising a plurality of identical parts respectively including a central hub section and a peripheral marginal section constituting substantially a complete convolution of the worm spiral with said hub and marginal sections being integral and of substantially uniform thickness over the entire areas thereof in the direction of the axis of the worm and with the marginal section of each part disposed in a plane arranged at an angle to the plane of the hub section of said part, said parts being assembled in intermeshing relation to each other with the hub sections in substantially parallel and axial aligned relation one to the other and with the marginal sections of an intermeshing pair of said identical parts spaced apart axially of the worm to receive a tooth of said tilting wheel therebetween, said hub sections each being offset to opposite sides respectively of a median plane perpendicular to the axis of said worm at opposite sides respectively of a plane axially bisecting said worm providing for interlocking of said parts in the assembled worm and forming radially extending shoulders on each part adapted to be engaged by radial edges respectively of the part interlocking therewith.
5. In a Venetian blind tilting mechanism including a tilting wheel having circumferentially spaced teeth, a worm cooperating with said toothed wheel and comprising a plurality of identical parts respectively including a central hub section and a peripheral marginal section constituting substantially a complete convolution of the worm spiral with said hub and marginal sections being integral and of substantially uniform thickness over the entire areas thereof in the direction of the axis of the worm and with the marginal section of each part disposed in a plane arranged at an angle to the plane of the hub section of said part, said parts being assembled in intermeshing relation to each other with the hub sections in substantially parallel and axial aligned relation one to the other and with the marginal sections of an intermeshing pair of said identical parts spaced apart axially of the worm to receive a tooth of said tilting wheel therebetween, said hub sections each being offset to opposite sides respectively of a median plane perpendicular to the axis of said worm at opposite sides respectively of a plane axially bisecting said worm providing for interlocking of said parts in the assembled worm and forming radially extending shoulders on each part adapted to be engaged by radial edges respectively of the part interlocking therewith.
6. In a Venetian blind tilting mechanism including a tilting wheel having circumferentially spaced teeth, a worm cooperating with said toothed wheel and comprising a plurality of identical parts respectively including a central hub section and a peripheral marginal section constituting substantially a complete convolution of the worm spiral with said hub and marginal sections being integral and of substantially uniform thickness over the entire areas thereof in the direction of the axis of the worm and with the marginal section of each part disposed in a plane arranged at an angle to the plane of the hub section of said part, said parts each being divided along a line extending radially from the axis to the peripheral edge thereof, said parts being assembled in intermeshing relation to each other with the hub sections in substantially parallel and axial aligned relation one to the other and with the marginal sections of an intermeshing pair of said identical parts spaced apart axially of the worm to receive a tooth of said tilting wheel therebetween, said hub sections each being offset to opposite sides respectively of a median plane perpendicular to the axis of said worm at opposite sides respectively of a plane axially bisecting said worm providing for interlocking of said parts in the assembled worm and forming radially extending shoulders on each part adapted to be engaged by radial edges respectively of the part interlocking therewith.
7. In a device of the character described, the combination of a bracket, a toothed tilting wheel pivotally mounted on the bracket, a double screw worm rotatably carried by the bracket and cooperating with the teeth on said tilting wheel, said worm comprising a pair of axially aligned hubs each provided with a segment of one convolution of the screw with the opposite ends of each of said segments in overlapping relation to the opposite ends respectively of the other of said segments and spaced apart laterally a sufficient distance to receive one of the teeth of the tilting wheel therebetween.

WALTER J. STUBER.
